UNITED STATES PATENT OFFICE.

CLAIRE H. PINGREE, OF HIGHLAND PARK, ILLINOIS.

TRUNK-BINDER.

1,158,841.

Specification of Letters Patent.

Patented Nov. 2, 1915.

Application filed December 11, 1914. Serial No. 876,699.

To all whom it may concern:

Be it known that I, CLAIRE H. PINGREE, citizen of the United States, residing at Highland Park, in the county of Lake and State of Illinois, have invented certain new and useful Improvements in Trunk Binders; and I do hereby declare the following to be a full, clear, and exact description of the invention, such as will enable others skilled in the art to which it appertains to make and use the same.

My invention relates to improvements in trunks and more particularly to binding and reinforcing means therefor which will prevent the trunk from breaking open in transit and eliminate undue wear and injury thereof.

Another object of my invention is to provide a trunk binder which consists of a link chain to surround the trunk and which is locked in such position thereon.

Another object is to provide means for retaining the binder upon the trunk which acts to reinforce the trunk as well and retain the binder so that it is prevented from coming into contact with the supporting surface for the trunk or other object.

Another object is to provide adjustable locking means for the binder which may be operated to lock the ends of the binder and to tighten the binder as desired.

A further object is to generally improve and simplify the construction and operation of trunk binders of the character described so as to render them more practical and reliable and efficient in operation without increasing the cost of manufacture thereof.

The above and additional objects are accomplished by such means as are illustrated in the accompanying drawings, described in the following specification and then more particularly pointed out in the claims.

With reference to the drawings, wherein I have illustrated the preferred embodiment of my invention as it is reduced to practice, and throughout the several views of which similar reference numerals designate corresponding parts, Figure 1 is a perspective view of a trunk showing my improved binder thereon, Fig. 2 is a transverse sectional view of a trunk equipped with my improved binder, Fig. 3 is a fragmentary transverse sectional view showing the locking means in detail, Fig. 4 is a fragmentary plan view of a portion of the binder showing it secured to one

of the binder receiving and retaining cleats, Fig. 5 is a transverse sectional view showing modified securing means for the binder, Fig. 6 is a sectional view of a modified form of retaining cleats, Fig. 7 is a perspective view of a tool for tightening the binder showing it in use, and Fig. 8 is a horizontal sectional view of the adjustable locking means.

Referring to the drawings by characters of reference A designates a trunk of the ordinary character which comprises a rectangular body 1 and a hinged lid or top 2 which is secured by the ordinary locking means 3.

Secured in vertical position in any suitable manner upon the outer faces of the side walls of the body 1 at points adjacent to the ends of said side walls are reinforcing binder retaining and engaging cleats 4. The cleats 4 terminate at their upper ends in spaced relation to the upper edge of the body and are provided with longitudinal binder receiving grooves 5 in their outer faces. Secured upon the sides of the lid 2 at points in alinement with the cleats 4 are similar binder receiving cleats 6 which terminate at their lower ends in spaced relation to the lower edge of the lid. Secured upon the top of the lid 2 at points in alinement with the cleats 6 are horizontal transverse cleats 7 which are similar to the ones 6 and have their grooves communicating with the grooves in the ones 6.

Secured upon the outer face of the bottom wall of the body 1 transversely thereof and in alinement with the side wall cleats 4 are similar, transverse cleats 8 which communicate at their ends with the grooves 5 in the cleats 4 and engage the lower ends of the cleats 4. While I have shown only two sets of cleats surrounding the trunk, it is to be understood that any number may be employed and that they may be arranged at any desired point relative to the trunk.

On the end walls of the trunk are secured vertical cleats 9 which coöperate with cleats 10 on the end walls of the lid and which are similar to the cleats 6. I provide a longitudinal cleat 11 on the top of the lid 2 and which extends transversely thereof and intersects the cleats 7. The cleat 11 is divided into three parts and the cleats 7 are formed with transverse openings 12 to allow for communication of the grooves 5 in the cleats

11 and 7. A longitudinal cleat 13, similar to the one 11 and arranged similarly with respect to the cleats 8 is carried upon the bottom wall of the trunk and communicates with the cleats 9, the cleats 8 being formed similarly to the ones 7 for coöperation with the cleat 13. Any number of series of cleats may be provided for the trunk longitudinally thereof or the longitudinally arranged cleats may be entirely dispensed with. For the several series of cleats I provide binders which comprise link chains 14 of any suitable material, preferably metal. These chains are positioned within the grooves 5 of the several cleats and are thus retained in position and prevented from contact with the other objects in that they are, in a sense countersunk in the cleats.

With reference to Fig. 7 of the drawings it will be seen that I have illustrated a tool designated 15 as an entirety for tightening the chain binders 14, said tool being of the ordinary construction and illustrated to indicate the manner in which the chains may be tightened. After the chains are tightened as desired, headed fastening elements 16 are inserted through the links thereof and into the cleats at suitable points so as to prevent slipping of the chains beyond a predetermined extent. The fastening elements 16 are arranged with relation to the links so that relative movement of the links is provided, the heads of the elements being larger than and engaging both sides of the links. Preferably secured to the upper ends of the cleats 4 at the front of the trunk, are locks 17. These locks are conveniently carried in the desired position in view of the fact that the upper end of the front cleats 4 are spaced from the upper edge of the body of the trunk and the locks are thus prevented from interfering with the opening and closing of the lid 2. The outer faces of the locks are flush with the outer faces of the cleats and possibility of derangement thereof is eliminated. Each of the locks comprises a casing 18 in which is mounted a spring dog 19. A staple 20 is carried by the casing 18 on the lower end thereof and is disposed within the grooves 5 so that one end of the adjacent chain may be secured thereto. Secured to the other end of the chain or binder is a lock bolt 21 which is formed with a longitudinal arrangement of ratchet teeth 22 on one face thereof. This bolt is to be inserted into the casing 18 in such manner that the spring dog 19 will engage with the teeth 22 and lock the bolt. By this arrangement, it will be seen that the bolt may be locked in various positions and thus provide for the tightening of the chains. A keyhole 23 is formed in the lock casing and opposite to the keyhole within the casing is a key engaging arm 24 which is carried by the dog

19. The key, not shown, engages the arm and forces the dog out of engagement with the teeth 22 on the bolt 21.

It is to be understood that while the hereinbefore described lock is preferred, any other suitable locking means may be employed. The longitudinal binders on the trunk are locked in position by locks 25 carried on the end walls of the trunk and coöperating with the binder chains 14 in the longitudinally arranged cleats. These locks 25 are arranged in a manner similar to the locks 17 and are identical as to construction.

Referring particularly to Fig. 5 wherein I have illustrated a modified form of my invention, 26 designates a part of a trunk or like receptacle, 27 a longitudinally grooved reinforcing and binder retaining cleat, and 28 a binder of the link chain type. As a means for positively holding the chain or binder 28 in the cleat 27, I place transverse securing cleats or strips 28^a on the cleat 27 at suitable points and secure them by suitable fastening elements 29. These strips 28^a terminate flush with the sides of the cleat 27 and prevent the binder from coming out of the groove in the cleat.

With reference to Fig. 6 wherein I have illustrated modified retaining means for the binder, 30 designates a portion of a trunk or like receptacle upon which are mounted spaced cleats 31 and 32. These cleats in being spaced provide a groove similar to the one 5 in the preferred form of cleat.

With reference to the foregoing description and accompanying drawings, it will be noted that I have provided a simple and effective binder for trunks and like receptacles, which may be quickly and easily positioned upon a trunk or removed and will materially increase the life of a trunk because of its reinforcing qualities.

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as claimed.

What is claimed is:

1. The combination with a trunk, of reinforcing and binder retaining cleats secured to the trunk, said cleats having alined binder receiving grooves disposed longitudinally therein and a flexible binder surrounding the trunk and slidable within the grooves and secured to the cleats.

2. The combination with a trunk, of re-

inforcing and binder retaining cleats secured to the trunk, said cleats having alined binder receiving grooves disposed longitudinally therein, a flexible binder surrounding the trunk and slideable within the grooves and secured to the cleats and means to lock the free ends of the binder.

3. The combination with a trunk, of a reinforcing and binder cleat arranged on the exterior of the body and provided with a longitudinal groove and having a lock casting at its upper end, a flexible binder extending around the trunk and having one of its terminals secured within the lock casing, locking means arranged within the lock casing and means carried by the other terminal of the flexible connection for coacting with the said locking means.

4. The combination with a trunk, of reinforcing and binder retaining cleats secured to the lid and body of the trunk and extending around the same both longitudinally and transversely thereof and longitudinally and transversely disposed flexible binders arranged within the said grooves and surrounding the trunk.

5. The combination with a trunk, of transverse cleats secured to the lid and body of the trunk and provided with longitudinal grooves, said transverse cleats having lateral openings, longitudinal cleats secured to the body and lid of the trunk and provided with grooves, said longitudinal cleats being located at the lateral openings of the transverse cleats, vertical cleats secured to the body and lid of the trunk and connected with the transverse and longitudinal cleats, chains extending transversely around the trunk and arranged in the transverse cleats

and in the adjacent vertical cleats, longitudinal chains arranged in the grooves of the longitudinal cleats and the adjacent vertical cleats, and locks arranged at the upper ends of the vertical cleats of the body and securing the ends of the chains together.

6. The combination with a trunk, of top and bottom cleats secured to the trunk at the top and bottom thereof and provided with longitudinal grooves, vertical cleats secured to the body and lid of the trunk and extending from the ends of the top and bottom cleats, said cleats having vertical grooves communicating with the grooves of the top and bottom cleats, a lock arranged at the front of the trunk at the upper end of the vertical cleats of the body, a chain surrounding the trunk and having one end secured to the lock and provided at its other end with a toothed bolt and means carried by the lock for engaging the bolt.

7. The combination with a trunk, of grooved cleats secured to the lid and body of the trunk and spaced apart at their adjacent ends, a chain surrounding the trunk and arranged in the grooves of the said cleats, means for locking the free ends of the chains to each other and means extending across the grooves of the cleats and retaining the chains therein without interfering with the longitudinal adjustment of the chains.

In testimony whereof I affix my signature in presence of two witnesses.

CLAIREE H. PINGREE.
